ELECTRON MULTIPLIER

Werner Flechsig, Berlin-Charlottenburg, Germany, assignor to the firm of Fernseh Aktiengesellschaft, Zehlendorf, near Berlin, Germany

Application June 17, 1938, Serial No. 214,179
In Germany June 26, 1937

8 Claims. (Cl. 250—175)

This invention relates to electron multiplier tubes and particularly to such tubes which employ a series of foraminated electrodes held at increasing potentials, at which electron multiplication by secondary emission takes place. Such electrodes, as is well known in the art, may consist entirely of a secondary emissive material such as nickel and others, or may consist of a base metal carrying a layer of high secondary emissivity such as produced by caesium. These tubes normally comprise a cathode, which may be of the thermionic or photoelectric type, a series of foraminated electrodes held at increasing potentials; and an electron-collecting anode to which the highest potential in the system is applied. In some cases it is desirable to modulate the electron stream in the tube by applying a modulating voltage to a control grid. The control grid can be placed next to the cathode, thus modulating the primary emission. It may, however, be desirable to subject the primary current to electron multiplication before modulation. This may be accomplished by inserting a control grid in the path of the electron stream after several stages of multiplication.

When the electron stream arrives near the control grid, it will have velocity components of largely varying values. This is because certain electrons arriving at a secondary emissive electrode of the type described will pass through the openings without impacting the solid portions of the electrode, and will continue their travel at increased speed. Other electrons will impact solid portions of the secondary emissive electrode and liberate secondary electrons, which will join the electron stream with a velocity considerably lower than that of the arriving primaries. Under these conditions the effectiveness of a control grid is greatly limited. By no means can 100% modulation be achieved.

It is the object of this invention to overcome this disadvantage; and to provide an electron multiplier in which a multiplied electron stream can be modulated without distortion.

Broadly considered, this invention provides for division of the electron stream after passing through several stages of multiplication into two components according to the electron velocities. The ratio of the two components into which the electron stream is divided is made in accordance with an applied modulating voltage. The high-velocity component of the electron stream is collected after division without further multiplication. The low-velocity component may be sub-

jected to further multiplication before it is finally collected and made use of in a work circuit.

The operation of the tube may now be explained in detail with the aid of the drawing wherein the figure is a view in section of a preferred form of my invention. 1 is a vacuum receptacle housing a thermionic cathode 2, adjacent to which a series of foraminated secondary emissive electrodes 3 are disposed. Modulation of the multiplied electron stream is to take place 10 after the last of the series of electrodes. At this point the vacuum receptacle is provided with a protrusion extending at a right angle from the main tube axis. In this protrusion control grid 4 and a further series of secondary emissive electrodes 5 are located. Control grid 4 is so biased that the resulting field will divert secondary electrons liberated at that electrode of series 3 closest to 4 towards the control grid, while high-velocity electrons passing through the secondary emissive electrode are not deviated from their initial path but travel past the control grid and finally arrive at a collector 6. 6 may be preferably given the shape of a cage, as indicated in the drawing, to prevent secondary electrons liberated by the impacting electron stream from re-entering the multiplier structure. The low-velocity stream of electrons drawn towards control grid 4 will be modulated by the modulating voltage applied to this grid, whereupon the modulated 20 electron stream is then subjected to further multiplication by impact upon secondary emissive electrodes 5. The modulated electron stream is finally collected at the anode 7. In this manner distortionless modulation of the electron stream 25 can be accomplished.

It is also possible to provide a second control grid between the cathode 2 and the first of the secondary emitting electrodes 3. Thus, two modulating voltages can then be applied, one of 40 which may be a radio-frequency carrier. It is, of course, also possible to provide a photocathode as the primary source of electrons to amplify the primary current and to introduce a carrier frequency at control grid 4.

The idea of the invention can be incorporated also in other electron multiplier structures inasmuch as the secondary emissive electrodes 5 need not be foraminated, but may be solid, whereby the electron path may have a zigzag or similar 50 shape. It is also possible, of course, to provide for one or several solid secondary emissive electrodes between the cathode 2 and the series of foraminated electrodes 3.

If the collector 6 is given the shape of a flat 55

plate, care must be taken to assure a low secondary emission ratio, which can be effected by using a carbonized nickel plate. It is also possible to provide a suppressor grid in front of collecting plate 6.

It may also be preferable, if seen necessary, to carbonize control grid 4 or to provide it with a coat of chromium oxide in order to prevent secondary emission by stray high-velocity electrons.

10. What I claim is:

1. An electron multiplier comprising a primary electron source, first means for multiplying by secondary emission the emission from said primary source, second means located at an angle to said first means for selecting the low-velocity component of the multiplied electron stream, said second means including in aligned relation a third means for modulating said low-velocity-component and fourth means for collecting the modulated low-velocity component, and fifth means for collecting the unmodulated high-velocity component of said multiplied electron stream, said fifth means being in alignment with said first means.

15 2. An electron multiplier comprising a primary electron source, first means for multiplying by secondary emission the emission from said primary source, second means located at an angle to said first means for selecting the low-velocity component of the multiplied electron stream, said second means including in aligned relation third means for modulating said low-velocity component, fourth means for collecting the unmodulated high-velocity component of said multiplied electron stream, said fifth means being in alignment with said first means.

20 3. An electron multiplier comprising a primary electron source, first means for multiplying by secondary emission the emission from said primary source, second means located at an angle to said first means for selecting the low-velocity component of the multiplied electron stream, said second means including in aligned relation third means for modulating said low-velocity component, fourth means for multiplying by secondary emission said low-velocity component and fifth means for collecting said multiplied modulated low-velocity component, and sixth means for collecting the unmodulated high-velocity component of said first-named multiplied electron stream, said sixth means being in alignment with said first means.

25 4. An electron multiplier comprising a cathode, an anode, an electron multiplying stage intermediate said anode and cathode in the path of electron flow from said cathode to said anode, means including an electron-diverting grid located adjacent said path of electron flow for diverting and modulating a low-velocity component of electrons from said path, and means for collecting said modulated low-velocity component.

30 5. An electron multiplier comprising an envelope having a main chamber and an extension chamber therefrom at an angle thereto, a cathode at one end of said main chamber, an anode at the other end of said main chamber, an electron multiplier stage in the path of electron flow from said cathode to said anode, said extension chamber opening into said main chamber at a location intermediate said electron multiplier stage and said anode, means in said extension chamber for diverting a low-velocity component of said electron flow into said extension chamber, and means for collecting said low-velocity component.

35 6. An electron multiplier comprising an envelope having a main chamber and an extension chamber therefrom at an angle thereto, a cathode at one end of said main chamber, an anode at the other end of said main chamber, an electron multiplier stage in the path of electron flow from said cathode to said anode, said extension chamber opening into said main chamber at a location intermediate said electron multiplier stage and said anode, a grid electrode at the entrance to said extension chamber for diverting and modulating a low-velocity component of said electron flow, and means in said extension chamber for amplifying and collecting said modulated low-velocity component.

40 7. An electron multiplier comprising means for producing a stream of electrons possessing various velocities, electrostatic means for dividing said electron stream into a high-velocity component and a low-velocity component, means for modulating said low-velocity component, and means for collecting said modulated low-velocity component, said two last-mentioned means being located in aligned relation at an angle to said first-mentioned means.

45 8. An electron multiplier comprising means for producing a stream of electrons possessing various velocities, electrostatic means for dividing said electron stream into a high-velocity component and a low-velocity component, means for modulating said low-velocity component, means for multiplying said modulated low-velocity component by secondary emission, and means for collecting said last-named component after multiplication, said three last-mentioned means being located in aligned relation at an angle to said first-mentioned means.

50 9. An electron multiplier comprising a first electrode assembly including a cathode for producing an electron stream and a plurality of foraminated secondary-emissive electrodes for multiplying said electron stream, a second electrode assembly adjacent said first electrode assembly including a control grid and an anode for diverting a portion of said multiplied electron stream, said second electrode assembly being located at an angle to said first electrode assembly, and an electron collector in alignment with said first electrode assembly for collecting the remaining portion of said multiplied electron stream.
